US00D712278S

(12) **United States Design Patent**
Adams et al.

(10) **Patent No.:** US D712,278 S
(45) **Date of Patent:** ** Sep. 2, 2014

(54) **CONTAINER AND OVERCAP**

(71) Applicants: **Mary Beth Adams**, Antioch, IL (US);
Daniel A. Andersen, Burlington, WI (US); **Jeffrey J. Christianson**, Oak Creek, WI (US); **Matthew Grossman**, Austin, TX (US); **Kit R. Morris**, Austin, TX (US); **Han Xin**, Shanghai (CN)

(72) Inventors: **Mary Beth Adams**, Antioch, IL (US);
Daniel A. Andersen, Burlington, WI (US); **Jeffrey J. Christianson**, Oak Creek, WI (US); **Matthew Grossman**, Austin, TX (US); **Kit R. Morris**, Austin, TX (US); **Han Xin**, Shanghai (CN)

(73) Assignee: **S.C. Johnson & Son, Inc.**, Racine, WI (US)

(**) Term: **14 Years**

(21) Appl. No.: **29/478,634**

(22) Filed: **Jan. 7, 2014**

(57) **CLAIM**

The ornamental design for a container and overcap, as shown and described.

DESCRIPTION

FIG. 1 is an isometric view of a top, front, and left side of an ornamental design for a container and overcap;

FIG. 2 is a front elevational view of the container and overcap of FIG. 1;

FIG. 3 is a rear elevational view of the container and overcap of FIG. 1;

FIG. 4 is a left side elevational view of the container and overcap of FIG. 1;

FIG. 5 is a right side elevational view of the container and overcap of FIG. 1; and,

FIG. 6 is a top plan view of the container and overcap of FIG. 1.

The bottom view forms no part of the claimed design.

1 Claim, 3 Drawing Sheets
